UNITED STATES PATENT OFFICE.

SLIMAN E. BOUHAROUN, OF WATERBURY, CONNECTICUT.

FOLDING CHAIR.

Application filed October 25, 1927. Serial No. 226,577.

This invention relates to furniture, and more particularly to a folding chair which may be quickly and easily collapsed into a small vertical space when not desired for use.

One object of this invention is to provide a folding chair of the above nature which is adapted to be collapsed by the action of swinging the back rest forwardly.

A further object is to provide a collapsible chair of the above nature in which the seat and back rest are adapted to drop by gravity into collapsed position upon the floor after the back rest has been swung forwardly.

A further object is to provide a folding chair of the above nature having an improved locking mechanism for preventing accidental collapse of the chair until desired.

A further object is to provide a folding chair of the above nature which will be relatively simple in construction, inexpensive to manufacture, easy to manipulate, ornamental in appearance, and very efficient and durable in use.

With these and other objects in view there have been illustrated on the accompanying drawings, two forms in which the invention may be conveniently embodied in practice.

Fig. 1 represents a side view of the folding chair as it appears when opened up ready for use.

Fig. 2 is a side view of the chair when partly collapsed and showing in dotted lines the appearance of the chair when fully collapsed.

Fig. 3 is a perspective view of the chair in open position.

Fig. 4 is a side view of the lower portion of a modified form of folding chair having a locking lever mechanism for preventing accidental collapse.

Fig. 5 is a front fragmentary view showing the rigid construction by means of which the chair legs are mounted in the base frame.

Referring now to the drawings in which like reference numerals denote corresponding parts throughout the several views, the base frame of the folding chair comprises a pair of parallel front and rear strips 10 and 11 adapted to lie flat upon the floor. The front and rear strips 10 and 11 are connected together by a pair of parallel side strips 12 and 13, as by rivets 14, as clearly shown in Figs. 3 and 5.

The upper part of the chair is supported upon four front and rear jointed legs, each leg comprising a lower section 15 pivoted to

the upturned ends 16 of the front and rear strips 10 and 11 by pivot pins 17. In order to form a rigid support for the lower leg sections 15, provision is made of small angle members 17^a riveted to said front and rear strips 10 and 11 and lying in contact with the lower ends of the lower leg sections 15, as most clearly shown in Fig. 5. In order to limit the pivotal motion of the lower leg sections 15, said sections are provided with laterally extending lugs 18, said lugs 18 being adapted to engage in shouldered recesses 19 formed in the upturned ends 16 of the front and rear strips 10 and 11.

Pivoted to the tops of the lower leg sections 15, as by pivot pins 20, are four upper front and rear leg sections 21, which are also pivoted by pins 22 to a horizontal chair seat 23, as clearly shown in the drawing. The two front upper leg sections 21 are connected together for producing greater rigidity by a cross-strip 24 located underneath the chair seat 23, while the two rear upper leg sections 21 are rigidly united by a rear rod 25.

The lower ends of the upper leg sections 21 are provided with lugs 26 similar to the lugs 18 and adapted to seat in shouldered recesses 27 in the upper ends of the lower leg sections 15, whereby the opening pivotal motion of the jointed leg sections will be limited in such a way that said legs will be normally maintained substantially vertical with the pivot pins 20 slightly out of line with the vertical line connecting the pivot pins 22 and 17. By means of this construction it will be seen that when the chair is in normal open position, the toggle action of the jointed leg sections will prevent it from collapsing.

In order to support the arms of the user, provision is made of a pair of flat arm rests 28, each of said arm rests being pivotally mounted on a pair of front and rear strips 29 and 30, said strips 29 and 30 being pivoted to said upper leg sections 21 by pins 31 and 32 having lateral lugs 33 similar to the lugs 18 and 26 for engaging in shouldered recesses 34 on the tops of said upper leg sections 21.

In order to support the back of the person using the chair, provision is made of a back rest 34 pivoted adjacent its lower end to the chair seat 23, as by a pair of hinges 35, said back rest 34 having brackets 36 secured thereto on either side of its lower end, as clearly shown in Fig. 3. The brackets 36 are connected to said back rest as by screws 37 and are provided with raised offset portions

38 in their upper ends. The offset portions 38 carry pivot lugs 39 which fit within slots 40 in the rear ends of connecting links 41. The connecting links 41 have their forward ends turned downwardly and pivoted to the forward upper leg sections 21 by pins 42 located above the chair seat 23. The lower ends of the brackets 36 are connected above the seat 23 to the upper ends of the adjacent upper leg sections 21 by two pairs of jointed links 43 and 44.

In operation, when it is desired to collapse the chair, it will only be necessary for the operator to pull forward upon the back rest 34, swinging it down about its hinges 35 in the direction of the arrow shown in Fig. 2. This will cause the connecting link 41 to move forwardly forcing the pivot pins 20 of the forward leg sections to move rearwardly. At the same time, the jointed links 43 and 44 will be pulled rearwardly forcing the upper rear leg sections 21 to rotate in a clockwise direction about their pivot pins 22. This will cause the central pivot pins 20 of the rear legs to move forwardly. The chair will thus be permitted to collapse under its own weight and will assume the position shown in dotted lines in Fig. 2. The shock of the fall is absorbed by a pair of bumpers 45 of rubber or other resilient material.

When it is desired to unfold the chair, all that is necessary is to lift the seat 23 upwardly, and then swing the back rest 34 rearwardly until the jointed legs assume the open position shown in Figs. 1 and 3.

In the modified form of the invention shown in Fig. 4, the chair is provided with locking mechanism for preventing the back from being swung forwardly until the operator desires to collapse the chair. This mechanism comprises a pair of arms 46 pivoted to the rear upper leg sections 21 by pins 47, and being provided with forwardly extending angular slots 48, having upturned front ends 49 for slidably receiving locking lugs 50.

While the present invention is adapted for general use wherever a collapsible chair which folds up into a small vertical space is desired, it will be found particularly useful in auditoriums, such as motion picture theatres where there is a large fire risk. In case of fire, the handles 51 of the locking levers will be pulled up, whereupon the chairs may be collapsed flat upon the floor by pulling the backs forwardly thereby affording the audience an unobstructed path to the exits.

While there have been disclosed in this specification two forms in which the invention may be embodied, it is to be understood that these forms are shown for the purpose of illustration only, and that the invention is not to be limited to the specific disclosures but may be modified and embodied in various other forms without departing from its spirit.

In short, the invention includes all the modifications and embodiments coming within the scope of the following claims.

Having thus fully described the invention, what is claimed as new, and for which it is desired to secure Letters Patent, is:

1. In a collapsible chair, a seat, a bottom frame, front and rear vertical jointed legs all pivoted to said seat and said bottom frame, a back hinged to said seat, and means operated by the swinging of said back for flexing said jointed legs and causing said chair to collapse into a small space upon said frame.

2. In a collapsible chair, a seat, a bottom frame, front and rear vertical jointed legs all pivoted to said seat and said bottom frame, a back hinged to said seat, link members connecting said back with the upper parts of said legs for causing said legs to flex at their joints when the back is swung forward so as to collapse said chair into a small vertical space upon said frame.

3. In a folding chair, a seat, a bottom frame adapted to rest upon the floor, collapsible front and rear legs pivoted to said seat and said bottom frame, a back hinged to said seat, a link member pivoted to said back above its seat hinge and to one of said front legs above said seat for causing said front legs to collapse when the back is swung forward.

4. In a folding chair, a seat, a bottom frame adapted to rest upon the floor, collapsible front and rear legs pivoted to said seat and said bottom frame, a back hinged to said seat, a jointed link member pivoted to said back below its seat hinge and to one of said rear legs above said seat for causing said rear legs to collapse when the back is swung forward.

5. In a folding chair, a bottom frame adapted to rest upon the floor, a seat connected to said frame by jointed front and rear legs, an arm rest located above the plane of said seat, and link members connecting the ends of said arm rest to the upper ends of said legs, whereby said arm rests will move downwardly toward said base when the legs are flexed for collapsing said chair.

6. In a folding chair, a bottom frame adapted to rest upon the floor, a seat, front and rear legs for supporting said seat, said legs comprising lower sections pivoted to said frame and upper sections pivoted to said lower sections and to said seat, and an arm rest located above the plane of said seat, link members connecting the ends of said arm rest to the upper ends of said legs, whereby said arm rests will move downwardly toward said base when the legs are flexed for collapsing said chair.

7. In a folding chair, a seat, a bottom frame adapted to rest upon the floor, collapsible front and rear legs pivoted to said seat and said bottom frame, a back hinged to said seat,

a link member pivoted to said back above its seat hinge and to one of said front legs above said seat for causing said front legs to collapse when the back is swung forward, a jointed link member pivoted to said back below its seat hinge and to one of said rear legs above said seat for causing said rear legs to collapse when the back is swung forward.

8. In a collapsible chair, a seat, a bottom frame, front and rear jointed legs all pivoted to said seat and said bottom frame,

means for flexing said jointed legs to permit said seat to move down upon said frame into collapsed position, locking means to render 15 said flexing means inoperative until it is desired to collapse the chair, said locking means comprising an arm having an angular slot pivoted to one of said rear legs, and a pin mounted on one of said front legs adapted to 20 slide in the slot of said arm.

In testimony whereof, I have affixed my signature to this specification.

SLIMAN E. BOUHAROUN.
